UNITED STATES PATENT OFFICE.

HERBERT T. JENKINS, OF PORTSMOUTH, NEW HAMPSHIRE, ASSIGNOR TO MORLEY
BUTTON MANUFACTURING COMPANY, OF PORTSMOUTH, NEW HAMPSHIRE, A COR-
PORATION OF MAINE.

BUTTON.

Application filed November 12, 1923. Serial No. 674,167.

To all whom it may concern:

Be it known that I, HERBERT T. JENKINS, a citizen of the United States, residing at Portsmouth, in the county of Rockingham

5 and State of New Hampshire, have invented new and useful Improvements in Buttons, of which the following is a specification.

This invention relates to buttons, and more particularly to that class of buttons 10 used on shoes, gaiters, etc. and which comprise a metal loop formed of wire, one end of which is extended to form a shank and is embedded and projects through in a head of hardened plastic material such as papier- 15 mâché and similar compositions. The shank is of approximately the same diameter throughout and terminates in a flange on the outer end thereof.

In buttons of this class the wire forming 20 the shank extending through the head is liable to become loosened so that the shank will twist in the head, and the head will be liable to crack and otherwise become useless. Moreover if the hole for the wire shank is 25 made small enough so that the wire forms a very tight fit therein, the head is liable to be split when the wire is driven therethrough or will split afterwards in use.

It is the object of this invention, therefore, 30 to construct a button of the class set forth wherein the shank extending from the loop of the button through the head is securely anchored in the head so that it will not twist, and moreover the anchoring 35 means embodied in this invention are of such form and are so positioned on the shank that while anchoring the shank in the button head firmly, both against rotation and longitudinal displacement, the button 40 will not become split when the wire is driven through the head and the loop formed thereon as hereinafter described.

The invention consists, therefore, of a button such as hereinafter described and partic- 45 ularly as pointed out in the claims.

Referring to the drawings:

Figure 1 is a plan view of my improved button.

Fig. 2 is a front elevation of the same.

50 Fig. 3 is a section of the head of my im-

proved button and a front elevation of the wire forming the loop and shank.

Fig. 4 is a sectional elevation taken on line 4—4 of Fig. 1.

Fig. 5 is a front elevation of the wire 55 from which the loop and shank are formed, the same being broken away to save space.

Fig. 6 is a front elevation of a modified form of wire.

Fig. 7 is a sectional plan taken on the 60 line 7—7 of Fig. 5.

Fig. 8 is a detail section taken on line 8—8 of Fig. 5.

Like numerals refer to like parts throughout the several views of the drawings. 65

In the drawings, excepting Fig. 6, 10 is the button head which in practice is preferably formed of hardened plastic material such as papier-mâché, although this invention is not confined to any particular material forming the head. The head 10 has a hole 12 punched therethrough and preferably countersunk at the opposite ends 13 and 14 thereof. 15 is a wire with a flange 16 on its upper end. 17 and 18 are locking 70 members provided upon the wire 15, said locking members being oppositely disposed.

The locking members are preferably tapered at their opposite ends and also are tapered from the central portion inwardly 80 toward the wire, thus forming oval shaped wedges. Each of the locking members 17 and 18 are spaced apart from the upper end of the wire 15 and one of the locking members 17 is positioned at a greater distance from the under side of the flange 16 than is the other locking member 18. The button is manufactured by driving the wire 15 through the button head in the hole 12 and then formed in the shape of a loop 19 90 as illustrated in Figs. 2 and 4 in a manner well known to those skilled in the art.

When the wire 15 is driven through the head of the button, the locking projections are being driven into the head of the button and in the completed button a portion of the head is located between the upper ends of each of said locking members and the lower side of the flange 16. The portion 20 within the head 10 forms a shank. 100

It will be seen by this construction and the method of manufacture that it is unnecessary to have the shank 20 form such a tight fit in the hole 12 as would be the case if the locking projections were not provided, thus the shank is firmly locked in the button head without splitting the same. The lower ends of the locking members, it will be noted, are spaced apart from the under side of the head and the said locking members are located entirely within the head of the button.

It will be noted that the outer edge of each of the locking members is inclined to ward the opposite ends of said members as well as the sides thereof, as illustrated in Fig. 8, thus the forcing apart of the material to allow the locking projections to enter the same is comparatively gradual.

The shape and location of the locking members contributes to the successful insertion of the wire forming the loop and shank without splitting the button and also contributes to the firmness of location of the shank within the button, and the splitting of the heads of the button is reduced to a negligible quantity while the loop is firmly affixed to the head, both as to resistance to rotation of the shank in the head and movement of the shank longitudinally thereof within the head.

It is evident that without departing from the spirit of my invention a single locking member may be employed instead of a pair of locking members as hereinbefore described and as shown in the drawings and some of the claims are drawn with this construction in view.

It will be noted, that as the lower end of the locking member 17 is nearer the lower end of the wire 15 than is the lower end of the locking member 18, the locking member 17 will begin to enter the head of the button before the locking member 18, and will be entirely enclosed within the button head before the locking member 18 is so enclosed and thus the strain upon the button, tending to split the same during the insertion of the wire 15, is lessened.

In Fig. 6 a modified form of my invention is illustrated in which 15' is the wire and 16' the flange on its upper end. Upon this wire are provided locking members 17' and 18', said locking members being oppositely disposed and inclined at an angle to the longitudinal median plane of the wire 15'. These locking projections are preferably tapered as in the form of locking projections 17 and 18 hereinbefore described. The wire 15' and its flange 16' with the locking projections 17' and 18' are forced into the head and an eye is formed on the wire in the same manner as hereinbefore set forth in relation to the wire 15 and the loop 19.

I claim:

1. A button comprising a head of hardened plastic material, an eye formed of a loop of wire, one end of said wire projecting through said head terminating in a flange and constituting a shank and a locking member on said shank within said head. 70

2. A button comprising a head of hardened plastic material, an eye formed of a loop of wire, one end of said wire projecting through said head and constituting a shank of approximately the same diameter throughout, a flange on the outer end of said shank and a locking member on said shank within said head. 75

80 3. A button comprising a head of hardened plastic material, an eye formed of a loop of wire, one end of said wire projecting through said head and constituting a shank of approximately the same diameter throughout, and an elongated locking member on said shank within said head. 85

90 4. A button comprising a head of hardened plastic material, an eye formed of a loop of wire, one end of said wire projecting through said head and constituting a shank of approximately the same diameter throughout, and an elongated locking member with tapered ends on said shank within the head. 95

95 5. A button comprising a head of hardened plastic material, an eye formed of a loop of wire, one end of said wire projecting through said head and constituting a shank of approximately the same diameter throughout, and a locking member on said shank within the head and spaced apart from the upper end of the shank. 100

105 6. A button comprising a head of hardened plastic material, an eye formed of a loop of wire, one end of said wire projecting through said head and constituting a shank of approximately the same diameter throughout, and a plurality of locking members spaced apart on said shank. 110

115 7. A button comprising a head of hardened plastic material, an eye formed of a loop of wire, one end of said wire projecting through said head and constituting a shank of approximately the same diameter throughout, and a pair of diametrically opposed locking members on said shank. 120

125 8. A button comprising a head of hardened plastic material, an eye formed of a loop of wire, one end of said wire projecting through said head and constituting a shank and an elongated locking member on said shank within said head inclined at an angle to the longitudinal medium plane of said shank. 130

135 9. A button comprising a head of hardened plastic material, an eye formed of a loop of wire, one end of said wire projecting through said head and constituting a shank and an elongated locking member 140

with tapered ends on said shank within the head and inclined at an angle to the longitudinal median plane of the shank and with tapered ends.

- 5 10. A button comprising a head of hardened plastic material, an eye formed of a loop of wire, one end of said wire projecting through said head and constituting a shank, and a pair of diametrically opposed 15 locking members on said shank inclined at

an angle to the longitudinal median plane thereof and inclined in opposite directions thereto.

In testimony whereof I have hereunto set my hand in presence of two subscribing ¹⁵ witnesses.

HERBERT T. JENKINS.
